United States Patent Office.

AMOS RANK, OF SALEM, OHIO.

Letters Patent No. 77,821, dated April 28, 1868.

IMPROVED PLATFORM-BRIDGE FOR RAILROAD-CARS.

The Schedule referred to in these Letters Patent and making part of the same.

TO ALL WHOM IT MAY CONCERN:

Be it known that I, AMOS RANK, of Salem, in the county of Columbiana, and State of Ohio, have invented a new and improved Foot-Bridge for the Platforms of Railroad-Cars; and I do hereby declare that the following is a full, clear, and exact description thereof, reference being had to the accompanying drawings, making a part of this specification, in which—

Figure 1 is a vertical section of the platforms of two cars coupled together, having the improved bridge applied to them.

Figure 2 is a top view of the bridge applied to the platforms of two cars.

Figure 3 is a perspective view of the improved bridge.

Similar letters of reference indicate corresponding parts in the three figures.

This invention relates to a new and improved construction of bridge-plates, which are designed to afford a footway between the platforms of railway-cars, for the safety of persons passing and repassing from one car to another.

The invention not only provides a substantial inflexible bridge between freight and passenger-cars coupled together, but it also provides for removing and replacing such a bridge at pleasure, and for allowing it to conform to the lateral and longitudinal motions of the cars.

The nature of my invention consists in constructing a bridge-plate which is adapted to serve as a footway between railroad-cars that are coupled together, with hooked recesses in its sides; of such shape and size as will allow the plates to be safely attached, without other fastenings, to the upright standards of the hand-rails on each side of the passage-way between cars, said recesses being so made as to allow the cars to have their natural lateral and longitudinal motions when under way, as will be hereinafter described.

To enable others skilled in the art to understand my invention, I will describe its construction and operation.

In the accompanying drawings, A A represent the platforms of two cars or coaches, provided with hand-rails *a a*, which are applied upon standards *b b*, and arranged in the usual well-known manner common to railroad-cars or coaches generally.

B represents a bridge, which forms a footway between the two platforms A A, and which is so constructed as to adapt it to receive the four vertical standards *b*, to which the hand-rails are applied, and thus enable these standards to serve in part as the fastenings for attaching the bridge to the platforms.

This bridge B may be constructed of cast metal of one piece, or it may be made of wrought-metal bars properly welded or riveted together. In order to secure lightness, the bridge may be made in the form of an open grating, of strap iron, united to a frame of proper shape, or it may even be made of wood.

In each longitudinal edge of the bridge, recesses *c c* are made, which leave double hooks for embracing the standards *b b* on both platforms, and preventing longitudinal as well as lateral displacement of the bridge when applied between the said standards, as shown in fig. 2. Said recesses are made of such length as will allow the longitudinal motion of the cars incident to the stopping and starting of a train, without crowding the bridge between said standards.

The length of the bridge B should be such that, when applied in place, its ends will extend over the ends of the platforms A A suitable distances to afford safe bearings thereon for it.

It will be seen, by reference to fig. 2, that the bridge B, as constructed, can neither work out of place laterally nor longitudinally; that it does not in any manner restrain the natural movements of the cars to which it is attached, as the recesses *c*, in the sides of this bridge, are of such length and shape as will prevent any accidental displacement of or injury to the bridge or the parts to which it is connected. It will also be seen that while this bridge cannot be moved out of position horizontally, it can be readily removed from the platforms and detached from the standards *b b* by lifting it as high as the hand-rails *a a*. In this way the bridge can be readily applied to and removed from the platforms of cars at pleasure, no other fastenings being required than those

afforded by the recesses *c c* and the standards of the hand-rails. If the recesses *c c* are made long enough, the bridge can be detached by lifting one end or side.

Having described my invention, what I claim as new, and desire to secure by Letters Patent, is—

A bridge or footing, B, constructed with recesses *c c*, or their equivalent, in its side edges, and adapted to be applied between railway-cars which are coupled together, substantially as described.

AMOS RANK.
